UNITED STATES PATENT OFFICE

95,545

DESIGN FOR A CLOTHESPIN OR SIMILAR ARTICLE

Edwin Reynolds, Vineland, N. J.

Application February 6, 1935, Serial No. 55,268

Term of patent 14 years

To all whom it may concern:

Be it known that I, Edwin Reynolds, a citizen of the United States, residing at Vineland, in the county of Cumberland and State of New Jersey, have invented a new, original, and ornamental Design for a Clothespin or Similar Article, of which the following is a specification, reference being had to the accompanying drawing, forming part thereof.

showing my new design; a dominant feature of which is the contour of the inner sides of its legs; and

I claim:

The ornamental design for a clothespin or similar article, substantially as shown and described.

EDWIN REYNOLDS.
